UNITED STATES PATENT OFFICE

2,000,467

COOLING, FREEZING AND HEATING APPARATUS

Theodore Lindseth, Coronado, Calif.

Application September 9, 1931, Serial No. 561,841

3 Claims. (Cl. 257—8)

My invention relates to cooling, freezing and heating apparatus, and the objects of my invention are:

First, to provide an apparatus of this class in which the air cooling medium is also used as a heating medium;

Second, to provide an apparatus of this class which is particularly adapted for small installations;

Third, to provide an apparatus of this class which enables a room or rooms connected therewith to be maintained at a given temperature anywhere from a point considerably below freezing to a moderately hot temperature;

Fourth, to provide an apparatus of this class which maintains a circulation of air in the room with which it is connected so as to maintain a uniform temperature throughout the room; and

Fifth, to provide on the whole a novelly constructed cooling, freezing and heating apparatus which is extremely simple of construction proportional to its functions, durable, efficient in its action, and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon, which form a part of this application, in which:

Figure 1 is a diagrammatical sectional view of the apparatus with parts and portions as shown in elevation; Fig. 2 is a transverse sectional view taken along section line 2—2 of Fig. 1; Fig. 3 is another transverse sectional view taken along section line 3—3 of Fig. 1; Fig. 4 is an enlarged transverse sectional view of the heating means taken through 4—4 of Fig. 3; and Fig. 5 is a diagrammatical view showing the thermostat and its relation to the refrigeration and heating units.

Similar characters of reference refer to similar parts and portions throughout the several views of the drawing.

Brine tank 1, air conduit coil 2, air intake conduit 3, blower 4, air outlet conduit 5, freezing coils 6 and 7, expansion valve 8, refrigerating unit 9, heater 10, and thermostat 11, constitute the principal parts and portions of my cooling, freezing and heating apparatus.

A brine tank 1 is located as near as feasible to the room or chamber C in which the tempera-

ture is to be controlled. The tank is filled with brine and the walls and top are provided with heat insulating material.

Coiled within the brine tank 1 is an air conduit 2 of relatively large cross section. The upper end of the coil 2 is connected to an intake conduit 3 which leads from the chamber C to the coil. Somewhere between the air intake conduit 3, there is provided a blower 4, so as to maintain a flow of air therethrough. The other end of the air conduit coil 2 is connected to an outlet conduit 5 which leads from the coil to the chamber C preferable near the floor thereof.

Arranged in the brine tank are a pair of freezing coils 6 and 7, the coil 6 being arranged within the air conduit coil 2, while the freezing coil 7 surrounds the other air conduit coil, as shown in Figs. 1 and 2. The freezing coils 6 and 7 are connected together and form a single length of pipe, the ends of which protrude from the brine tank, the intake pipe being provided with a suitable expansion valve 8.

Located in any suitable relation to the brine tank is a refrigerating unit 9 of conventional design comprising a motor 9a, a compressor 9b driven thereby, and a suitable condenser 9c.

The freezing coils 6 and 7, as well as the air intake coil 2, are spaced from the bottom of the brine tank 1. Supported below the several coils and contiguous to the bottom of said brine tank is an electrically operated immersion heater which may be in the form of an open loop, the ends 10a of which protrude from the side of the brine tank, as shown in Fig. 3.

The heater comprises a core or heating element 10b such as carbon or resistance wire, which is adapted to become heated when current passes therethrough, the core surrounded by suitable insulating material 10c, which is retained in place by suitable jacket or casing 10d. The insulation prevents actual contact between the brine and the heating element 10b, thereby eliminating the possibility of a short circuit.

The ends 10a of the heater 10 protrude through the side wall of the tank and are connected to a suitable source of electricity. The ends may be enclosed in a suitable box 10d mounted on the outside of the brine tank.

If it is desired to cool the chamber, the refrigerating unit 9 is started, which enables the freezing coils 6 and 7 to reduce the temperature of the brine in the tank 1, at the same time the blower circulates air through the air conduit 2, thereupon the brine cools the air therein. By regulating the expansion valve 8 of the refrigerating unit 9, the temperature of the air in the chamber C may be controlled.

erating unit 9, the action of the freezing coils may be controlled, so that the temperature of the brine is regulated, and the temperature of the same is brought to the desired point.

- 5 5 Should it be desired to warm the chamber, the refrigerating unit is turned off and the circuit through the heater 10 is turned on, whereby the brine is warmed so as to, in turn, warm the air within the air conduit coil, thus the temperature of the chamber may be held at any point throughout an extremely wide range.

10 15 The above may be accomplished automatically by means of a suitable thermostat controlled switch 11 arranged to control the heating unit or the refrigerating unit, thus permitting a continuous range of temperature control beginning below and terminating above normal temperature.

15 20 Although the liquid within the tank 1 is referred to as brine, any liquid having a low freezing point and a high vaporization point may be used. Certain kinds of oils may be used as well as many solutions. If liquids which do not conduct electricity are used, the heating element need not be provided with insulation.

25 30 It is obvious from the construction as illustrated in the drawing and described in the foregoing specification, that there is provided a cooling, freezing and heating apparatus as aimed at and set forth in the objects of the invention, and though I have shown and described a particular construction, combination and arrangement of parts and portions, I do not wish to be limited to this particular construction, 35 combination and arrangement, but desire to include in the scope of my invention the construction, combination and arrangement substantially as set forth in the appended claims.

35 40 Having thus described my invention, what I claim as new and desire to secure by Letters Patent is:

- 45 50 1. In a cooling, freezing and heating apparatus, an air circulating system including a chamber, an air conduit connected therewith, and fan means for maintaining circulation of air through said conduit and chamber, a portion of said conduit arranged in a coil, a tank for receiving said coil, a temperature transmitting medium contained in said tank in direct contact with said coil and immersing the same, freezing coils positioned and arranged both in-

side and outside of the coil in said conduit and immersed in said temperature transmitting medium, a heating medium positioned in alignment with and below the coil in said conduit immersed in and in direct contact with the temperature transmitting medium in said tank, said freezing coils forming guide means for directing the temperature transmitting mediums as heated around said conduit coil.

5 10 15 20 25 2. In a cooling, freezing and heating apparatus, an air circulating system including a chamber, an air conduit connected therewith, and means for maintaining circulation of air through said conduit and chamber, a portion of said conduit arranged in a coil, a tank for receiving said coil, a temperature transmitting medium contained in said tank in direct contact with and immersing said coil, freezing coils positioned and arranged both inside and outside of the coil in said conduit and in said temperature transmitting medium, a heating medium positioned in alignment with and below the coil in said conduit immersed in and in direct contact with the temperature transmitting medium in said tank, said freezing coils forming guide means for directing the temperature transmitting mediums as heated around said conduit coil, and an automatic control means common to both said cooling means and said heating means.

30 35 40 45 50 3. In a cooling, freezing and heating apparatus, an air circulating system including a chamber in which the air is to be cooled or heated, an air conduit connected at its opposite ends to the upper and lower sides of said chamber, a coil intermediate its ends, a suction fan intermediate said coil and the upper end of said conduit, a tank in which said coil is mounted, brine in said tank in direct contact with said coil and immersing the same, freezing coils positioned inside of said coil in said conduit, other freezing coils positioned and arranged outside of the coil in said conduit and all immersed in said brine, an electric immersion heater positioned in alignment with and directly below said coil in said conduit and immersed in said brine in said tank, said freezing coils forming guide means for directing the heat from said electrical immersion heater as heated around said conduit coil.

THEODORE LINDSETH.
